UNITED STATES PATENT OFFICE

HERMAN HOLLERITH, JR., OF RIVERTON, NEW JERSEY, ASSIGNOR, BY MESNE ASSIGNMENTS, TO RADIO CORPORATION OF AMERICA, OF NEW YORK, N. Y., A CORPORATION OF DELAWARE

CONTROL MEANS FOR RADIO APPARATUS

Application filed April 30, 1925, Serial No. 27,008. Renewed October 31, 1931.

This invention relates to radio or wireless telegraph apparatus, and more particularly to means for adjusting variable reactors of the type employed in such apparatus.

5 Radio receiving instruments comprising a plurality of circuits which include variable reactors, such, for example, as condensers, have heretofore been provided with a shaft common to the movable elements of each of said reactors, whereby the latter may be simultaneously adjusted to tune the said circuits. For the most part, however, radio receiving instruments are provided with a plurality of widely separated and independent 10 15 15 operable members for use in separately tuning the various circuits.

In the first-named arrangement it is impossible to independently adjust the various reactors, and, since it is practically impossible to construct two reactors having identical characteristics throughout the range of adjustment, and since very minute differences in adjustment of the reactors in some circuits may cause relatively great differences 20 25 30 35 in the operation of the instrument, the use of a common control shaft has not proven entirely satisfactory. Moreover, if the receiving instrument is so constructed that certain reactors may be simultaneously adjusted with satisfactory results, it may be provided with one or more additional variable reactors which are preferably adjusted independently of the first-named group.

The use of independently operable and 35 40 45 widely separated adjusting members for each of the variable reactors employed is objectionable due to the increased cost of the apparatus, the difficulty and time consumed in tuning, and the resulting increase in the size of the instrument.

An object of the present invention is to provide a device whereby a plurality of reactors may be equally and simultaneously adjusted by a single manual operation, and yet one which is so constructed that the control or adjusting members, with their associated reactors, are not connected, and are independently operable throughout the entire range of adjustment.

50 Another object of the invention is to pro-

vide a compact arrangement of parts whereby two reactors or two groups of reactors may be simultaneously operated and yet independently adjusted throughout their operative range.

55 Another object of the invention is to provide apparatus of the character described with a novel arrangement of indicator dials for indicating the predetermined positions to which the reactors should be adjusted in order to tune the receiving instrument to a desired wave length or station.

A further object is to provide novel means for transmitting motion from the adjusting members or thumb wheels to the reactors to 60 65 be adjusted and the indicator dials. These and other objects will appear more fully hereinafter.

Three forms which the inventive idea may assume are shown in the accompanying drawings, which drawings, however, are for the purpose of illustration only and are not to be taken as defining the limits of the invention, reference being had to the appended claims 70 75 for this purpose.

In the drawings,

Fig. 1 is a top plan view illustrating the apparatus of the present invention installed on a supporting panel;

Fig. 2 is a sectional side elevation taken 80 on the line 2—2 of Fig. 1;

Fig. 3 is a side elevation partly in section taken on the line 3—3 of Fig. 1;

Fig. 4 is a sectional view taken on the line 4—4 of Fig. 2;

Fig. 5 is a side elevation partly in section illustrating a second embodiment of the invention;

Fig. 6 is a side elevation illustrating still another embodiment of the invention;

Fig. 7 is a top plan view of the arrangement shown in Fig. 6; and

Fig. 8 is a detail view illustrating one form of stop means that may be employed.

Referring to the drawings wherein like 95 reference characters refer to like parts throughout the several views, and particularly to Figs. 1 to 4, 1 is a support or panel of any suitable type such as is usually employed in radio receiving instruments. This 100

supporting member is preferably provided with an elongated opening 2 and a substantially rectangular opening 3. Mounted in any suitable manner at the rear side of the panel 1, as by means of screws 4 securing the same to the panel 1 on the opposite sides of said openings, is a frame for supporting the control apparatus in convenient operating position. Preferably this frame comprises a pair of plates or end members 5 which are rigidly held in spaced relation by means of a suitable number of spacing members or rods 6.

The frame plates 5 constitute means for supporting the variable reactors. In the form shown in the drawings these reactors are diagrammatically illustrated by the members 7 which represent the end frame members of a plurality of variable condensers, the plates 8 of which are not shown. It is to be understood, however, that the invention is not limited to the control or adjustment of variable condensers nor to the control of only two reactors. Each of the condenser elements 7 is secured by means of screws 8 and nuts 9 to the outer face of one of the frame plates 5 or in any other suitable manner. Rotatably mounted in the condenser frame members 7 are the usual shafts 10, which extend inwardly towards each other between the planes of the frame members 5, and which carry the movable plates (not illustrated) of the condensers. Mounted on the left-hand shaft 10, as viewed in Figs. 2 and 4, adjacent the inner end thereof, is a pulley 11 provided with an outwardly extending hub portion 11a. A threaded member 12 extends through portion 11a into engagement with the shaft 10 for rigidly attaching the pulley 11 thereto. A pulley 13 which is preferably provided with an inwardly extending hub portion 13a terminating in a circular flange 13b, and with an outwardly extending hub portion 13c, is fixedly secured to the inner end of the opposite shaft 10, as by means of the threaded members 14. Indicator drums 15, 16, which in the present instance are formed as short cylinders having a diameter greater than that of the pulleys, are secured to the inner surfaces of pulley 11 and flange portion 13b respectively, by means of screws 17.

Suitable means are provided for rotating the shafts 10 and their attached drums 15, 16 by a single manual operation but said means is so constructed that the said shafts are independently adjustable. In the form shown, a rod 18 is fixedly secured at its opposite ends in the frame members 5. For this purpose a sleeve 19 is secured to each end of the rod 18 as by means of a screw 20 and each sleeve is provided with a reduced portion which extends through an opening in the frame member 5. The outer ends of the said sleeves may be upset as indicated at 21 for rigidly securing the same to said frame member, or

they may be fixed in position in any other suitable way. Mounted for free rotary movement on the rod 18 is a sleeve 22 provided on its outer end with a pulley 23 which lies in the same vertical plane as the pulley 11. The opposite or inner end of the sleeve 22 is provided with a flange portion 22a, to which is pinned or otherwise suitably secured, a thumb wheel 24. Mounted adjacent the opposite end of rod 18 and in the same vertical plane as the pulley 13, is a pulley 25 provided with an inwardly extending hub portion and on the latter is rigidly secured, in any suitable manner, a second thumb wheel 26 which is disposed in a plane parallel to the thumb wheel 24 and so closely adjacent that both wheels may be simultaneously rotated by the thumb or a single finger. To facilitate the adjustment of the wheels 24 and 26, the peripheries thereof are preferably knurled in some suitable manner.

Means are provided for transmitting motion from the pulleys 23 and 25 to the pulleys 11 and 13 respectively. In the form shown this means comprises a flexible member 27 for each pair of pulleys. One end of the flexible member is passed through an opening in the side of the groove of the larger pulley and fixedly secured to the latter as by means of a suitable pin 28. Preferably, the opposite end of the flexible member 27 also extends through an opening in the outer wall of the groove of the larger pulley and is secured to a resilient member or spring 29 which is fixedly attached to the pulley as by means of a pin 30. Preferably, means are provided for limiting the arc through which the shafts 10, and the indicator dials secured thereto, may be adjusted. As shown, a pair of pins 31 are secured to each of the pulleys 11 and 13, the said pins projecting outwardly from said pulleys toward the frame members 5. Interposed in the path of the pins 31 are stop members 32 of any suitable type secured to the frame members 5. To facilitate the marking of the peripheries of the indicator dials 15, 16 a strip of paper or other suitable material 33 may be secured to the periphery of said dials, as by means of the spring clamps 34.

A cover plate 35 is preferably provided on the upper surface of the panel over the dials and the thumb wheels. In the form shown this plate is provided with a pair of openings in register with the openings 2, 3 in the panel 1, and the peripheries of the thumb wheels 24, 26 extend upwardly through the elongated opening 2 for a convenient distance. The peripheries of the indicator dials 15, 16 extend outwardly into the plane of panel 1 in register with the opening 3 in the latter. This opening and the registering opening in the cover plate 35 may be provided with a hinged cover 36 carrying a transparent plate 37. An indicating marker may be provided

in the center of the opening 3 below the cover 36. In the form shown this member comprises a U-shaped wire 38 secured at its opposite ends to the cover plate 35.

- 5 If it is desired to simultaneously and equal-
ly vary the reactances, the operator may ro-
tate both of the wheels 24 and 26 by a single
finger placed on the two wheels. The ro-
tation of the latter is transmitted through pul-
leys 23 and 25, members 27, pulleys 11 and 13,
and shafts 10 to the movable plates of the con-
densers. Differences in the adjustment that
must be made to compensate for the inherent
differences that always exist between two
15 condensers or other types of reactances, or
relative angular adjustments that must be in-
troduced between the condensers to compen-
sate for differences in the other elements of
the circuits being tuned, are readily made by
20 independent rotation of one of the thumb
wheels, since the latter are not inter-con-
nected.

When the instrument has been adjusted to
the desired wave length or station, the trans-
parent cover 36, 37 may be raised and a dis-
tinguishing mark inscribed on the peripheries
25 of the dials 15, 16 in alignment with the
marker or pointer 38. Thereafter the circuits
may be quickly tuned to any one of a number
30 of stations in a simple and expeditious man-
ner.

The general arrangement of the embodiment
35 of the invention illustrated in Figure
5 is similar to that of the first embodiment
described. As shown each thumb wheel 24, 26
has motion transmitting means which com-
prises a pinion 39 rotatably mounted on the
40 rod 18 and rigidly connected in any desired
manner to the corresponding thumb wheel 24,
26, and this pinion meshes with a gear 40 that
is rigidly secured in any desired manner to
the corresponding indicator drum 15, 16 and
shaft 10. In order to provide an extremely
compact device the drums 15, 16 are provided
45 adjacent their peripheries with arcuate slots
41 which extend through an angle of slightly
more than 180°. The rod 18 carrying the
thumb wheels 24, 26 extends through the regis-
tering slots 41 and is supported in the frame
50 plates 5 in any suitable manner as has previ-
ously been described. Rotation of the thumb
wheels 24, 26 is transmitted by the pinions
and gears to the respective drums and rotat-
able elements or shafts 10 in a manner that
55 will be readily understood. The rod 18 and
slots 41 constitute stop means for limiting
the rotary movement of the indicator drums
and it will therefore be apparent that the lat-
ter need not extend through 360°. This
60 arrangement may be provided with a suitable
cover plate and index markers as desired.

Figs. 6, 7, and 8 illustrate a third embodiment
65 of the invention wherein a rod 18' fixed-
ly secured at its opposite ends in the frame
plates 5, constitutes a support for the rotat-

ably mounted thumb wheels 42, 43. Secured
in any desired manner to the inner faces of
the thumb wheels and concentric therewith
are a pair of closely adjacent indicator drums
44, 45. A gear 46 is secured to the outer face
70 of each of the thumb wheels and these gears
mesh with gears 47 rigidly secured to the in-
ner ends of the shafts 10. Preferably gears
46, 47 have a ratio of one to two whereby
rotation of the wheels 42, 43 and consequently
drums 44, 45 through 360° results in a rota-
tion of shafts 10 through 180°. A cover
75 plate 48 (Fig. 7) is preferably secured to the
upper surface of panel 1. Through suitable
openings in this cover plate project the thumb
wheels 42, 43 and between the latter the plate
is provided with suitable pointers 49 for indi-
80 cating the position of adjustment of the
drums 44, 45. If desired, stop means may be
provided for limiting the rotation of the ro-
tatable elements. As shown in Fig. 8 gears
85 47 may be provided with a small pin 50 sec-
ured in any suitable manner, as by means of
solder, between a pair of its teeth for this pur-
pose.

There is thus provided a very compact ap-
paratus for controlling the adjustment of a
pair of variable reactors or two groups
of reactors. Moreover, it will be seen that
one thumb wheel may be employed for
95 adjusting a single reactance while the
other thumb wheel is employed for ad-
justing a plurality of reactors. The in-
dicators are closely adjacent and may be
easily read. Due to the contiguous mount-
100 ing of the thumb wheels the same may be
simultaneously rotated by a single movement
or independently adjusted as desired. While
two forms of motion transmitting means
have been illustrated in the drawings, it will
105 be apparent that these means are shown by
way of example only. Reference is there-
fore to be had to the appended claims for a
definition of the limits of the invention.

What is claimed is:—

1. A device of the class described comprising
a panel, variable reactors having rotat-
able elements mounted at the rear of said
panel, a pair of concentrically mounted
wheels extending partially through the panel
110 at right angles thereto, a pair of juxtaposed
indicator dials associated with said wheels
and disposed in planes at right angles to said
panel, and means for transmitting rotary mo-
tion from said wheels to said rotatable ele-
ments.

2. A device of the class described comprising
a panel having an opening therein, a pair
of unconnected thumb wheels partially pro-
jecting through said opening, a plurality of
reactors, a pair of closely adjacent indicators
115 readable simultaneously from a common in-
dex, and means whereby said reactors and
indicators are severally adjustable by rota-
tion of said wheels.

3. A device of the class described comprising a panel having an opening therein, a pair of parallel thumb wheels partially projecting through said opening, a pair of juxtaposed parallel indicator wheels associated with said thumb wheels, said indicator wheels being concentrically mounted for rotary movement, a plurality of reactors, and means whereby said reactors are severally adjustable by rotation of said wheels. 70
4. A device of the class described comprising a panel, frame plates, variable reactors having rotatable elements secured to said plates, a pair of wheels extending through the panel, adjacent indicator dials comprising a drum associated with each of said wheels, removable record strips mounted on the periphery of each of the drums, and means for transmitting rotary motion from said wheels to said rotatable elements. 75
5. A device of the class described comprising a panel having an opening therein, frame plates mounted at the rear of said panel, variable reactors having rotatable elements secured to said plates, a pair of wheels extending through the opening in said panel in planes at right angles to the latter, contiguous indicators associated with each of said wheels, removable strips carried by the peripheries of said indicators, means for removably securing said strips to said indicators and motion transmitting means interposed between each wheel and rotatable element. 80
6. A device of the class described comprising supporting means, variable reactors having rotatable elements secured thereto, a rod supported by said means, a pair of manually operable members rotatably mounted on said rod, indicators associated with each of said members, and means for transmitting motion from each of said members to separate rotatable elements. 85
7. A device of the class described comprising supporting means, variable reactors having rotatable elements secured thereto, a rod supported by said means, a pair of manually operable members rotatably mounted on said rod, a pair of contiguous indicators one associated with each of said members, and means for transmitting motion from each of said members to separate rotatable elements. 90
8. A device of the class described comprising, in combination with a panel, a plurality of reactors, means for adjusting said reactors, and means for operating said last-named means including a pair of closely adjacent but unconnected rotatable thumb wheels disposed in parallel planes, a portion of said wheels projecting through an opening in said panel, whereby they are capable of simultaneous adjustment by one finger, or capable of independent relative movement for separate adjustment. 95
9. A device of the class described comprising, in combination with a panel, a plurality of reactors, means for adjusting said reactors, means for operating said last-named means including a pair of closely adjacent but unconnected rotatable thumb wheels disposed in parallel planes, a portion of said wheels projecting through an opening in said panel, whereby they are capable of simultaneous adjustment by one finger or capable of independent relative movement for separate adjustment, and a pair of indicators rotatable in adjacent parallel planes and respectively operated by the respective thumb wheels. 100
10. A device of the class described comprising a panel having an opening therein, a pair of closely adjacent but unconnected thumb wheels projecting partially through said opening, whereby they are capable of either independent adjustment or simultaneous adjustment by one finger, means on which said wheels are concentrically mounted, a plurality of reactors, and means whereby said reactors are severally adjustable by rotation of said wheels. 105
11. A device of the class described comprising a panel having an opening therein, a pair of closely adjacent but unconnected thumb wheels projecting partially through said opening, whereby they are capable of either independent adjustment or simultaneous adjustment by one finger, a plurality of reactors, a plurality of indicators, means on which said indicators are concentrically mounted for rotary movement and means whereby said reactors and indicators are severally adjustable by rotation of said wheels. 110
12. A device of the class described comprising a panel having an opening therein, a pair of unconnected thumb wheels projecting through said opening, whereby they are capable of either independent adjustment or simultaneous adjustment by one finger, a plurality of reactors, a pair of closely adjacent indicator drums, a common index for said drums, and means whereby said reactors and drums are severally adjustable by rotation of said wheels. 115
13. A device of the class described comprising, in combination with a panel, a frame, a pair of closely adjacent thumb wheels mounted for independent rotation in said frame, a portion of said wheels projecting through an opening in said panel, a pair of shafts rotatably mounted in said frame, a pair of drums, each of said drums being connected to one of said shafts, and means for transmitting rotary movement from the thumb wheels to said shafts. 120
14. A device of the class described comprising a support having openings therein, a frame, a rod rigidly secured to said frame, a pair of closely adjacent thumb wheels mounted for independent rotary motion on said rod, a portion of said wheels projecting through an opening in said support, a 125
- 130

- pair of shafts mounted for independent rotation in said frame, a drum on each of said shafts, and means for transmitting rotary motion from the thumb wheels to said shafts.
15. A device of the class described comprising, in combination with a support having a pair of openings therein, a frame secured to said support, a pair of wheels mounted for independent rotation in said frame, said wheels being disposed in parallel planes normal to the surface of said support and a portion of said wheels extending through one of the openings in said support, a pair of shafts mounted in said frame, a drum secured to each of said shafts, said drums being mounted in planes parallel to said wheels and in alinement with the other opening in said support, and means for transmitting rotary movement from the wheels to said shafts.
16. A device of the class described comprising a support, a frame secured thereto, a pair of shafts independently journaled in said frame, drums secured to said shafts, said drums being disposed in parallel planes, a rod, a pair of wheels mounted for independent rotary movement on said rod, and means for transmitting rotary movement from the wheels to said shafts.
17. A device of the class described comprising a support, a frame secured thereto, a pair of shafts independently journaled in said frame, drums secured to said shafts, said drums being disposed in parallel planes, a rod, a pair of wheels mounted for independent rotary movement on said rod, and means including a resilient member for transmitting movement from said wheels to said shafts.
18. A device of the class described comprising a support having a pair of openings therein, a frame, a pair of closely adjacent wheels mounted for independent rotary movement on said frame, said wheels being disposed in parallel planes and projecting through one of the openings in said support, a pair of shafts carried by said frame, resistance means secured to said shafts, drums carried by said shafts, said drums being mounted in planes parallel to said wheels, the peripheries of said drums extending into the plane of said support adjacent the other opening in said support, and motion transmitting means interposed between said wheels and shafts.
19. A device of the class described comprising a support having a pair of openings therein, a frame secured to said support, a pair of closely adjacent wheels mounted for independent rotary movement in said frame, said wheels projecting through one of the openings in said support, a pair of shafts journaled in said frame, drums secured to said shaft in the plane of the other of said openings, and means for transmitting motion from the wheels to said shafts.
20. A device of the class described comprising a support having an opening therein, reactors having rotatable elements, and means for rotating each of said elements including a pair of parallel thumb wheels operable through said opening, gearing intermediate said wheels and elements, and parallel indicators secured to each of said wheels.
21. A device of the class described comprising a support, frame means secured to said support, a reactor having a rotatable element, secured to said frame means; a gear secured to said element, a rod mounted in said frame means, a wheel rotatably mounted on said rod, an indicator secured to said wheel, and a pinion secured to said wheel and having operative engagement with said gear.
22. A device of the class described comprising a support having an opening therein, means including a pair of frame plates secured to the support, variable reactors having rotatable elements secured to said plates, a rod mounted in said plates, wheels rotatably mounted on said rod, the peripheries of said wheels extending through said opening, a drum secured to each of said wheels, and motion transmitting means interposed between the wheels and each of said rotatable elements whereby rotation of said wheels is transmitted to said elements in a two to one ratio.
23. A device of the class described comprising supporting means, variable reactors having rotatable elements secured to said means, a rod carried by said means, a pair of manually operable members rotatably mounted on said rod, indicators for each of said manually operable members secured to the inner faces of the latter and closely adjacent one to the other, pinions secured to the outer faces of each of said members, and gears secured to said rotatable elements in mesh with said pinions.
24. A tuning device, comprising a frame, said frame being adapted to be secured to a panel, a plurality of wheels rotatably coaxially mounted in said frame independently of each other but with their peripheral surfaces in contiguous relation so as to be operable by the contact of a single finger tip and so as to extend partially through an opening in said panel, a plurality of drums rotatably mounted in said frame, indicia on the peripheral surfaces of said drums, a tuning element mounted in association with each of said drums, and means whereby said wheels are arranged to actuate said drums and tuning elements.
25. A tuning device comprising a frame, said frame being adapted to be secured to a panel, a plurality of wheels rotatably coaxially mounted in said frame independently of each other but with their peripheral surfaces in contiguous relation so as to be op-

erable by the contact of a single finger tip and so as to extend partially through an opening in said panel, and means whereby each of said wheels is arranged to actuate a related tuning element.

26. A tuning device comprising a frame, said frame being adapted to be secured to a panel, a plurality of wheels rotatably coaxially mounted in said frame independently of each other but with their peripheral surfaces in contiguous relation so as to be operable by the contact of a single finger tip and so as to extend partially through an opening in said panel, means whereby each of said wheels is arranged to actuate a related tuning element, and means for indicating the adjustment of said element.

27. A tuning device comprising a frame, said frame being adapted to be secured to a panel, a plurality of wheels rotatably coaxially mounted in said frame independently of each other but with their peripheral surfaces in contiguous relation so as to be operable by the contact of a single finger tip and so as to extend partially through an opening in said panel, peripheral means on each of said wheels to facilitate rotation thereof by means of the finger tip, and means whereby each of said wheels is arranged to actuate a related tuning element.

28. A radio tuning apparatus comprising a plurality of condenser units mounted with their rotors in alinement and a controller member connected to each rotor, said controller members being mounted close together so that they may be operated by the movement of one hand, said members and their rotors being independently operable and each requiring the application of external force directly to its controller in order to turn it, and a single face plate through which an arc of each controller member extends for digital engagement.

29. A dial mechanism for radio receivers comprising, in combination, a dial adapted to be secured to an instrument shaft and carrying a pulley of relatively large diameter, a knob, pulley means of substantially smaller diameter than said large pulley and connected to said knob, and belt means connected between the pulley means and the pulley carried by the dial and frictionally engaged between flanges of the pulley means whereby when said knob is turned said dial will be driven at a reduced ratio through the medium of said belt, said belt means having an end connected through spring means to said dial.

30. A control mechanism for radio apparatus comprising, in combination, a control shaft, pulley means of relatively large diameter mounted on said shaft, pulley means of substantially smaller diameter than said first named pulley means, flexible belt drive means connected between said pulley means, where-

by when said second named pulley means is turned said dial is positively driven at a reduced ratio through the medium of said belt means, and spring tensioning means attached to said belt means to exert a tension thereon at all times, said spring tensioning means being carried by and movable with said first named pulley means and said pulley means having an opening through which the belt means is carried into connection with the spring tensioning means.

31. Dial mechanism for radio apparatus including, in combination, a dial member, pulley means carried thereby, belt means connected with said pulley means in frictional engagement therewith, a portion of said belt means being secured out of frictional engagement with said pulley by connection with the dial whereby said portion of the belt means moves therewith, and spring tension means in said connection.

32. In dial mechanism for radio apparatus, the combination with a dial member and driven pulley means thereon, of driving means therefor including flexible belt means wrapped at least in part about said pulley means in contact with a surface thereof, a portion of said flexible belt means being withdrawn from contact with said surface, and spring tension means connected with the dial member for applying tension to the flexible belt means through said withdrawn portion thereof.

33. In an adjusting device for a variable reactor having a rotatable element, a driving pulley, a driven pulley connected to said rotatable element, flexible means for conveying motion between said pulleys, said means being wrapped about said pulleys, and means carried by the driven pulley for maintaining said flexible means under tension, said means being connected with a portion of the flexible motion conveying means withdrawn from the wrapped position about the driven pulley and including a tension spring secured to said pulley.

34. In an adjusting device for variable radio tuning means having a rotatable element, the combination of a driving pulley, a driven pulley connected to said rotatable element, flexible means for conveying motion between said pulleys, and means entirely carried by the driven pulley for rotation therewith, and connected between said pulley and the flexible motion conveying means for maintaining said flexible motion conveying means under tension.

35. In an adjusting device for variable radio tuning means having a movable tuning element, the combination of a movable driving member therefor, a movable dial member connected to said movable tuning element, flexible belt means for conveying motion between said driving member and said dial member, and means entirely car-

ried by the dial member for rotation therewith, said last named means being connected between said dial member and the flexible belt means for maintaining said flexible belt 5 means under tension.

36. In an adjusting device for variable radio tuning means having a movable tuning element, the combination of a driving pulley, an indicator drum connected to said 10 movable tuning element, flexible belt means for conveying motion between said pulley and said drum, and means entirely carried by the indicator drum for rotation therewith, said last named means being connected between said drum and the flexible belt means 15 for maintaining said flexible belt means under tension.

In testimony whereof I have signed this specification.
